UNITED STATES PATENT OFFICE.

HANS M. BOE, OF MINNEAPOLIS, MINNESOTA.

PISTON FOR GREASE-GUNS.

1,377,660.

Specification of Letters Patent. Patented May 10, 1921.

Application filed July 8, 1918. Serial No. 243,976.

To all whom it may concern:

Be it known that I, HANS M. BOE, a citizen of the United States, resident of Minneapolis, county of Hennepin, State of Minnesota, have invented certain new and useful Improvements in Pistons for Grease-Guns, of which the following is a specification.

In the manufacture of grease guns or apparatus for dispensing grease or oils, it has been necessary to provide pistons of different weight according to the character of the grease or oil to be dispensed or delivered. For a heavy oil, a heavy piston must be used and for a lighter oil a correspondingly lighter piston must be provided to insure the successful operation of the device.

The object of my invention is to provide the grease container with a piston of such construction that it can be readily adapted for heavy or light lubricating material and so constructed that the container may be filled without the necessity of removing the entire piston therefrom. A further object is to provide a piston adapted for tanks of different diameter and a combination piston which may be of greater diameter than the cover used for refilling the container.

A further object is to provide a piston which can be readily adapted for containers of different diameters.

The invention consists generally in various constructions and combinations, all as hereinafter described and particularly pointed out in the claims.

35 In the accompanying drawings forming part of this specification,

Figure 1 is a vertical sectional view through a container and piston embodying my invention,

40 Fig. 2 is a plan view of the piston removed from the container,

Fig. 3 is a detail sectional view, showing the piston ring and the piston proper fitting therein,

45 Fig. 4 is a bottom view of the piston,

Fig. 5 is a sectional view of a portion of the container, of small size, showing the piston adapted for this diameter of container.

50 In the drawing, 2 represents a container

having a bottom 3, exit opening 4 and a ring 5 whereon a cover 6 is mounted. A stud 7 is provided on the cover to receive a collar 8 whereto the series of forked arms 9 are pivoted having ends 10 for engaging the shanks of bolts 11, said arms being fulcrumed on the cover for pressing it down to its seat. 12 is a wing nut mounted on the stud 7 and engaging the collar 8. 13 is an air intake valve and 14 an indicator carried by the cover. 15 represents the outer ring or section of the piston. This ring is preferably made up of a series of wooden rings (though metal may be used) placed one upon the other and secured together and having a bail 16 for convenience in lifting it out of the container or placing it therein. This bail may be used for lifting the piston to the top of the container preliminary to re-loading and particularly if the diameter of the tank is greater than the cover for said tank. This piston may have a peripheral covering 17 of canvas or other suitable material to contact with the inner walls of the container. This piston is adapted for feeding or dispensing light oils, as it will float thereon and gradually slide down to the bottom of the tank as the lubricating material is discharged.

Within the central opening 18 in this piston I provide a secondary piston 19 having preferably a central core or block with a peripheral fabric 20, preferably canvas, secured thereto and having outwardly turned edges to contact with the peripheral edges of plates 21 which are secured to the top and bottom of the auxiliary piston by a bolt 22. This bolt has a nut 23 at one end thereof and a head 24 is provided at the opposite end in position to be engaged and concealed by a cap 25. The bottom of this cap forms a valve for closing the port 4 in case the piston should drop to the lower end of the tank before the air has been entirely exhausted from the pipe. The cap in the bottom of the piston has the function of closing the port when the tank is emptied of lubricating material, thereby preventing the remaining air charge from escaping through the discharge pipe and hose.

The piston 19 has a loop 26 thereon for the attachment of a line from the indicator, so that the position of the piston will always determine the location of the indicator 5 and the amount that has been discharged from the container. The line from the indicator may be connected to the bail of the ring instead of to the inner section, if preferred. The plates 21 are preferably of 10 iron and exert considerable downward force on the piston, causing it to hold its place in the container with a body of heavy oil or grease therein, without however, sinking to the bottom of the container as usually is the 15 case and would be true of this application if this piston was used with a lighter grade of oil than was intended for a piston of this type. This weighted piston keeps the contents of the container leveled upon top and 20 insures a more accurate measure. It also overcomes the tendency of the lubricating material to funnel down toward the discharge opening. The core being of wood, the upper and lower plates may be removed 25 and the piston used in light oil without the removable disks, but when the piston is used in heavy oil or grease, one or both of the plates 21 are mounted on the bolt so that the piston will then be of sufficient 30 weight to properly feed the lubricating material out of the tank. The float part of the piston and piston ring may be made of metal or from cork or other suitable material, but the piston only affects the measuring 35 of the lubricant to the extent that it keeps the top of the contents of the container level, or nearly so. The under side of the piston ring 15 is provided with clips 27 on which the inner piston may rest when 40 inserted in the ring and the peripheral covering 20, of canvas or other suitable material, encircling the piston 19, will have sufficient friction with the ring to hold the inner piston in place and the indicator cable 45 29 may be connected to the loop 26 that is mounted on the upper end of the bolt 22, the weight of the piston holding it in place in the ring though provision may be made for connecting it to the ring, if preferred. 50 With this construction of piston it is not necessary to use a larger cover for the container than is required for inserting the piston 19. In such case the floating piston ring is lifted by means of its bail up under 55 the head of the container while it is being re-filled. The diameter of the opening for a container is necessarily limited on account of the difficulty of getting an air-tight joint, even with a cover locking device. I have 60 found that a seven inch opening is about the limit, while the diameter of the tank may be twelve inches or more.

From the foregoing it will be noted that the outer or ring section is preferably of

light floating material, while the inner section has preferably upper and lower disks or plates with a lighter filling material between them, the plates being removable so that the inner section may be used with the plates or not, as preferred. 70

I claim as my invention:

1. The combination, with a grease or oil container, of a floating piston ring fitting therein, a piston fitting within said ring and separable therefrom without removal 75 of the ring from the container and an indicating device for said container having a flexible connection with said piston.

2. The combination, with a container, of a piston fitting therein and comprising an 80 inner and an outer section, said inner section being separable from said outer section without removal of the outer section from the container and having means for attaching it to an indicating device cable. 85

3. The combination, with a container, of a piston fitting therein and comprising an inner and an outer section, said outer section being comparatively light in weight and said inner section being comparatively heavy 90 and having means for connecting it with an indicating device cable, the inner section being separable from the outer section without removal of the latter from the container. 95

4. The combination, with a container, of a piston fitting therein and comprising an inner and an outer section, said inner section having a comparatively light core and metal plates secured to the upper and under side thereof, said sections being held together by frictional contact and said inner section having means for connection with an indicator cable. 100

5. The combination, with a container, of 105 a piston fitting therein and comprising an outer piston ring composed of comparatively light material having clips on the under side thereof, projecting into the opening therethrough, and a comparatively heavy 110 inner section fitting within the opening in said ring and seated on said clips, and flexible means connected to said piston.

6. The combination, with a container adapted to contain a lubricating agent and 115 having a discharge opening in the bottom thereof and a removable cover, of a piston fitting within said container and comprising an inner and an outer section, said piston being mounted to float on the lubricating material within said container and said removable inner section being removable without removal of the outer section from the container for allowing the filling of said container through the cover opening without 120 removing said outer section. 125

7. The combination, with a container adapted to contain a lubricating agent hav-

ing a discharge opening in the bottom thereof and a removable cover, of a piston fitting within said container and comprising a comparatively light outer ring section and an 5 inner disk section fitting within said ring section and said inner disk section having a yielding peripheral covering for engaging the wall of said outer section, said piston

floating on the material in said container and said disk section being removable for 10 filling purposes independently of the outer section.

In witness whereof I have hereunto set my hand this 21st day of June 1918.

HANS M. BOE.
